(57) **CLAIM**

The ornamental design for a particle measurement device, as shown and described herein.

DESCRIPTION

FIG. 1 is a perspective view illustrating a mount and a resonance unit assembled into a particle measurement device of the present design;

FIG. 2 is an exploded view of the mount and the resonance unit of a particle measurement device of the present design;

FIG. 3 is a front view illustrating the particle measurement device of the present design;

FIG. 4 is a rear view illustrating the particle measurement device of the present design;

FIG. 5 is a left side view illustrating the particle measurement device of the present design;

FIG. 6 is a right side view illustrating the particle measurement device of the present design;

FIG. 7 is a plan view illustrating the particle measurement device of the present design;

FIG. 8 is a bottom view illustrating the particle measurement device of the present design;

FIG. 9 is a perspective view of a mount included in the particle measurement device;

FIG. 10 is a front view of the mount;

FIG. 11 is a rear view of the mount;

FIG. 12 is a left side view of the mount;

FIG. 13 is a right side view of the mount;

FIG. 14 is a plan view of the mount;

FIG. 15 is a bottom view of the mount;

FIG. 16 is a perspective view of a resonance unit included in the particle measurement device;

FIG. 17 is a front view of the resonance unit;

FIG. 18 is a rear view of the resonance unit;

FIG. 19 is a left side view of the resonance unit;

FIG. 20 is a right side view of the resonance unit;

FIG. 21 is a plan view of the resonance unit; and,

FIG. 22 is a bottom view of the resonance unit.
